O. B. PECK, JR.

CENTRIFUGAL CONCENTRATOR

Filed June 23, 1924

Orrin B. Peck Jr.

UNITED STATES PATENT OFFICE.

ORRIN B. PECK, JR., OF LOS ANGELES, CALIFORNIA.

CENTRIFUGAL CONCENTRATOR.

Application filed June 23, 1924. Serial No. 721,648.

To all whom it may concern:

Be it known that I, ORRIN B. PECK, Jr., a citizen of the United States, residing at 1433 West 48th St., in the city of Los Angeles, State of California, have invented certain new and useful Improvements in Centrifugal Concentrators, of which the following is a specification.

My invention relates to that type of centrifugal concentrators which operate in successive cycles alternately accumulating a bed or load of concentrates in a rotating vessel, and then discharging the same without stopping the vessel, and in which an internal rotatable longitudinally movable core member is employed to function with the vessel for accomplishing the purposes of the concentrator, the longitudinal movements of the core in part, being controlled by liquid pressure of a hydraulic cylinder in operating communication with the core member, together with pressure of liquid on the core at the feed end of the vessel, incident to centrifugal force and accretion of concentrates in the vessel.

In the drawing, Fig. 1, is partly a side elevation, and partly a central longitudinal vertical section of my concentrator, showing the internal member or core moved to its nearest approach to the small or feed end of the concentrating vessel, in position for commencement of a concentrating period, the governor operating to effect opening of the feed valve to the vessel, and such valve being shown in that position.

Fig. 2, is similar to Fig. 1, but showing the core forced back to the discharge end of the vessel, caused primarily through accretion of concentrates; the feed of material closed off and water turned on to assist in discharge of heavier constituents, or concentrates, and the core in position for commencement of the discharge period.

It will be understood, as has been described in my allowed application for Letters Patent, Serial No. 666277, filed Oct. 3d, 1923, that in this type of concentrator the core member is somewhat shorter in length than the internal length of the concentrating vessel, which permits longitudinal movement of the core within the vessel, and that in operation the vessel is rotated at a high speed during the concentrating period, and the core at the beginning of each cycle is positioned at the small or feed end of the vessel, also that during concentration it is

gradually forced lengthways by operating pressure under high centrifugal impetus on the material and liquid fed into the vessel, towards the opposite or large end of the vessel, which movement is suitably and yieldably resisted by liquid pressure in the hydraulic cylinder, as above stated; also that this endways movement is incident to, or primarily caused by accretion of concentrates in the vessel, as will hereinafter be explained, and will continue until the core is forced to its nearest approach to the large end of the vessel; that the time of such movement of the core constitutes the concentrating period, and its duration is not predetermined, as it is governed by the rapidity with which heavier constituents or concentrates accumulate in the vessel.

It will be further understood that during the unloading or concentrate discharge period of the cycle, the vessel is rotated at a relatively slow speed without stopping, and the core is automatically forced back by pressure of the liquid in the hydraulic cylinder, to its initial position in the vessel, preparatory to the commencement of another cycle, and my invention herein described and claimed relates more particularly to these features in coordination with means for hydraulically effecting and controlling the functioning of members for feeding material as well as water to the vessel and stopping the same, governed by the accretion of heavier constituents in the underdetermined period of the cycle.

In carrying out my present invention I provide a rotatable conical shaped cylinder or concentrating vessel 2, illustrated partly in longitudinal section and partly in side elevation in both Figs. 1 and 2, of the drawings. At the large end of this vessel there is an enlargement 3, in which is formed an internal annular chamber, having comparatively small discharge opening 4, located in a circumferential row which extends from the chamber through the wall of the vessel, for discharge of liquid and material from the vessel.

The vessel at this end is provided with a head 5, which is rigidly and concentrically mounted on and supported by a rotatable hollow shaft 6, which is journaled in boxes 7 and 8 respectively, mounted on the upper end of stands 9 and 10, these stands in turn, being supported on a base plate 11, of the concentrator. The shaft 6 is provided with

a pulley 12, by which rotation is imparted to it from any suitable source of power by a belt, not shown, and in this way the concentrating vessel is revolved at the speed which may be desired.

The small end of the vessel is also provided with a head 13, which has a suitable hollow trunnion 14, which is journalled in a box 15, mounted on the upper end of a stand 16, also superimposed on the bed plate of the concentrator.

Within the concentrating vessel is a core member 17, which is somewhat smaller in diameter and also somewhat shorter than the internal length of the vessel. This core is tapering in form substantially the same as is the internal circumferential wall of the vessel, and is of diameter so when the core is positioned nearest to the small or feed end of the vessel, as illustrated in Fig. 1, there will be a comparatively small annular space or channel 18, around between its exterior and the interior wall or surface of the vessel, which in operation serves as a concentrating channel or passage.

This is the position of the core for commencement of the concentrating period. The concentrating passage is illustrated as enlarged in Fig. 2 by movement of the core, as will hereinafter be explained, and an accretion of concentrates or heavier constituents are illustrated in the same.

The core is somewhat in the nature of a large plug, although appearing in the drawings, within the vessel, in longitudinal section. It is intended to be smooth on its circumferential surface, and is securely mounted on the overhanging end of a shaft 19, which is journalled in the hollow of the shaft 6, passing through such hollow and extending into the vessel suitably to support and carry the core therein.

This shaft also extends through and out of the opposite end of the hollow shaft, a desired distance, so as to be journalled at outer end, in a box 20, mounted on the upper part of a stand 21, which is supported on the bed plate of the concentrator as shown.

As means for rotating the shaft 19, and the core, there is a pulley 22, of suitable size mounted on the shaft, which may be driven by a belt, not shown, at any speed required.

Surrounding the enlargement 3, of the vessel, there is provided a hollow housing or launder 23, with comparatively thin walls, located and held in place on the bed plate of the concentrator as illustrated, and is provided with an annular slot or opening 24, through its wall around adjacent to the enlargement, in radial alignment with the discharge holes 4, in position to receive the discharge of liquid and material from the vessel and permit the same to flow from

an opening 25 through the lower part of the launder, to a place of further disposition.

As means for feeding material to the vessel during the concentrating period and water during the discharge period, and for stopping such respective feeds at the appropriate times, I provide a feed valve embodying a suitable body or cylindrical chambered portion 26, preferably having an inwardly extended ledge 27 in its chamber, adapted to form a suitable valve seat.

The main portion of the chamber of the valve is of size and appropriately formed for movement of a valve closing disc 28 so in it, as illustrated.

The upper end of the valve is preferably provided with a material feed pipe 29, the flow channel of which, into the valve, is positioned and adapted to be closed by proper movement of the disc 28 over said opening, as shown in Fig. 2.

Preferably near the lower portion of the valve body is connected a water or other suitable liquid supply pipe 30. This pipe is connected below the seat shoulder 27, so when the disc 28 is in downward position, as shown in Fig. 1, the water pipe will be closed to the upper part of the valve.

Suitably connected to the valve body above the seat ledge 27 is a comparatively short pipe 31 passing through the hollow trunnion; and somewhat into the vessel at the feed end, to deliver feed into this end. The valve is suitably supported by a bracket 32, attached to the journal stand 16, as illustrated in the drawings.

As means for operating the feed valve, there is a suitable hydraulic cylinder 33, provided with a piston head 34 therein, which is carried by a rod 35.

This rod passes out of the cylinder through a packing box 36, and into the feed valve through a packing box 37, as shown, where it properly engages and carries the closure disc 28 in the valve.

This rod 35 is of length and the hydraulic cylinder and valve and their respective members are so relatively located that the rod will carry the disc and properly seat the same to open and close the feed and water passages in the valve, as illustrated, depending on which way the rod is moved by hydraulic action in the cylinder.

To supply liquid under requisite pressure to operate the hydraulic cylinder as desired, there are pipes 39 and 40 connected to the cylinder, the former serving when it is desired to close the water feed and open material feed, as shown in Fig. 1, and the pipe 40 when the reverse action is desired, as shown in Fig. 2.

Preferably in extended axial alignment with the shaft 19, or substantially so, there is provided a hydraulic cylinder 41, securely

but removably connected to the journal stand 21, as illustrated in the drawings. The end of the shaft 19 extends through its box 20, into the cylinder a greater or less distance, as shown, depending on the position of the core 17. Within the cylinder is a suitable piston head 42, which is rotatably attached to the end of the shaft 19, through appropriate non-rotatable members 43, 44 and 45 respectively, and the rotatable disc member 46 attached to the shaft, also the bearing balls 47, as shown.

The members which effect rotatable engagement of the piston head and the end of the core shaft, as just explained, in this way serve to transmit liquid pressure from the cylinder, through the shaft, to yieldably resist, as desired, longitudinal movement of the core towards the discharge end of the vessel during concentration, also as the agency by which the core is automatically forced towards the fed end of the vessel during the discharge of concentrates.

Liquid which is supplied to the hydraulic cylinder under requisite pressure, through a pipe 48, is preferably from a yieldable or elastic source, as from an accumulator drum or receiver 49, as illustrated in the drawing, the upper part of the drum of the accumulator serving as an air chamber, which is supplied with air to afford elasticity to movement of the liquid. The liquid is forced into the accumulator drum under desired pressure by suitable means, as by a force pump, not shown, connecting with a pipe 49'. As additional means of regulating the liquid pressure to the cylinder there is an adjustable relief valve 50 employed, of any suitable type.

The outer end of the hydraulic cylinder is provided with a head 51, which preferably in part forms a chamber 52 and is provided with a preferably central opening 53 from the cylinder to the chamber. Within the chamber is provided a disc 54 having a stem portion 55 which protrudes through the opening 53 a short distance into the cylinder.

The disc forms a closure member for the opening 53, and is normally held or seated over such opening to close the same, by yieldable means, as a rubber cushion 56, as shown in Fig. 1. The outer side of the chamber 52, is closed by a removable cap 57, which also affords access to the yieldable cushion and disc when desired.

The pipe 40 from the hydraulic cylinder 41 is connected to the chamber 52 and water under pressure from the chamber is supplied through it at the appropriate time to operate the cylinder and stop the feed of material as herein below explained.

The protruding end of the stud 55, into the cylinder is in position and adapted to contact with a member 58 on the piston head and force the disc back, opening the

passage 53 into the chamber 52, as shown in Fig. 2, when the piston head has been forced to the position through accretion of concentrates in the channel 18.

This result in causing the cylinder 33 to function and close off the material feed to the vessel, which ends the undetermined concentrating period, and starts the feed of water for the discharge period.

It will be seen in this way the duration of the concentrating period through which material is fed to the vessel is primarily governed and determined by the accretion of heavier constituents in the vessel, and secondarily, by forcing back of the disc 54 through movement of the piston head 42 to its extreme outward position in the cylinder, as shown in Fig. 2.

It follows, as is also illustrated in Fig. 2, that at the time feed of material is closed off by the valve, feed of water is started by the same movement of the piston rod 35.

After feed of material has been stopped and feed of water started to the vessel by the means described, the speed of rotation of the vessel should be much reduced for the discharge of accumulated heavier constituents, which constitutes the discharge period, but the speed of the core should not be reduced.

This condition of reduced vessel speed lessens the centrifugal force both on the bedded concentrates within the vessel, and the water then being fed into it, rendering the concentrates relatively easy to dislodge and discharge, and much reducing the end-ways pressure on the core towards the large end of the vessel, so the core is, at this time during discharge of the heavier constituents, quickly forced by the pressure in the cylinder 41, which has not been reduced, to the small end of the vessel in position for commencement of another concentrating period.

When the accumulated concentrates have been discharged from the vessel, the end of the discharge period having been reached, the speed of the vessel is intended to be accelerated sufficiently for concentration, the water fed to the vessel should be stopped and feed of material started.

As means for automatically stopping the water and starting the material feed when the vessel is sufficiently accelerated for this purpose, I provide a governor 59 of an ordinary suitable adjustable type, and furnish it with a suitable reciprocable plug 60, secured to the running gear of the governor, so the plug will be moved up or down as there is variation in the speed of the balls of the governor.

There is a pipe 61 suitably connected to the barrel of the governor as shown, from any appropriate source of liquid under pressure. The pipe 39 is also connected to the valve as shown, in position with relation to

the pipe 61, so a port or opening 62 in the plug 60 will be brought in registration with these two pipes and afford a liquid flow passage between them, which will permit liquid under pressure to pass from the pipe 61 to the cylinder 41, and through movement of the cylinder piston head 34, operate the parts of the feed valve into position shown in Fig. 1, stopping the water feed and starting the material feed.

The governor is driven from the vessel shaft by a belt 63, as shown, and does not receive impetus enough to open the flow port through the valve plug during the discharge period or until the concentrating vessel has practically attained concentrating speed.

To afford escape for liquid which may be statically in either end of the cylinder 33 when it is desired to force the piston to that end, there is provided suitable small escape pipes 64 in the respective hydraulic pipes serving the cylinder, as shown in the drawings. It will be further understood that the pressure of liquid which is supplied through the governor to function the cylinder 33, should be somewhat less than the pressure from the cylinder 44, to move it in the opposite direction, as the latter movement will be required while the governor is operating at full speed and liquid through it will then be effective in the cylinder 33, and the pressure to effect opposite movement will therefore have to be stronger than the opposing pressure.

In operation, during the concentrating period, the vessel is rotated at a desired comparatively high rate of speed, and the core member is rotated at a desired differential speed to that of the vessel, these speeds being adjusted separately and relatively to effect the concentration wanted.

Under these conditions a suitable volume of material mixed with the water for treatment is fed to the vessel through the feed pipe 31, into the space between the small end of the vessel and that end of the core, thence flowing into the concentrating channel or passage, where the heavier portions to be separated and recovered, accumulate in said channel in a progressive accretion or bed. 18', as illustrated in Fig. 2, while the lighter or waste portions are hydraulically scoured by the liquid passing through the concentrating channel as a result of operation, and are washed or carried on through such channel to discharge from the vessel through the openings 4, and into the launder, passing on out through the opening 25, in the lower part of the launder for further desired disposition.

During this time of concentration, the vessel operating at a comparatively high speed, the liquid and material which accumulates in the feed end of the vessel, as the same are being fed therein, are subjected to highly

developed centrifugal force, resulting in a hydraulic pressure, strongly tending to force the core endways from the feed end of the vessel towards the large end. This pressure is much augmented as the concentrates bed in the concentrating channel, from the fact that such bedding gradually fills in the concentrating passage and decreases the size of the flow channel for the liquid and material from the feed end. This endways pressure on the core, as above explained, is transmitted through the shaft 19, and its associated part, to the liquid in the hydraulic cylinder, so such liquid forms a resisting energy to the pressure on the end of the core to force the latter towards the large end of the cylinder.

The liquid pressure in the hydraulic cylinder may be in part, or largely adjusted through the regulating or relief valve 50, so as to balance with the pressure of liquid accumulated in the small end of the vessel, in a manner to yield to the latter pressure as desired, permitting the core to be gradually forced back towards the large end of the vessel, resulting in maintaining the flow passage for material in the concentrating channel of suitable and desired size, while accretion of concentrates therein progresses. This continues until the core has been forced to its extreme position at the large end of the vessel, which has enlarged the channel to its maximum size, permitting the same to have become largely filled with bedded concentrates.

When the core has been fully moved to the large end of the vessel, the feed of material for concentration is closed off by the feed valve; the speed of the concentrating vessel very much reduced and clean liquid introduced, pipe 30, resulting, during the low speed of the vessel, in a relatively low centrifugal force and relatively low pressure of liquid in the feed end of the vessel, thereby changing the balance of pressure between this point and the liquid in the hydraulic cylinder 41, so that the pressure in the latter cylinder will be relatively largely in excess, which condition will force the core again to the small or feed end of the vessel, while the bedded concentrates are washed out under the low condition of centrifugal force, restoring the initial relative positions of the core and the vessel for commencement of another cycle of operation.

The concentrates are flowed from the vessel, while being discharged, through the same openings 4, as was the waste during the concentrating period of the cycle, but may be diverted by any suitable means to a desired place, as they flow from the opening in the lower part of the launder.

The concentrates having been discharged from the vessel, it is then accelerated to its

suitable high speed for concentration; the feed of clean water discontinued; the feed of material for concentration restored, and the operation may be repeated, thus progressing in successive cycles.

It will be understood that it is not intended that the concentrating vessel should be stopped to state of rest during the discharge period, but that its speed should 10 be much reduced, as has been already explained, although no injury will be sustained if it should reach a state of rest during such time.

What I regard as new and desire to secure 15 by Letters Patent is:

1. In a centrifugal concentrator the combination of a rotatable vessel, a differentially rotatable longitudinally movable core within the vessel, adapted in operation to 20 be pressed towards the discharge end of the vessel, yieldable hydraulic means for resisting such endways pressure, means for feeding material and feeding water to said vessel at desired time, and means for hydraulically operating said feed means, substantially as described.

2. In a centrifugal concentrator, the combination of a rotatable concentrating vessel, a differentially rotatable longitudinally 30 movable core within the vessel adapted in operation to be hydraulically pressed towards the discharge end of the vessel, hydraulically actuated means for feeding material to the vessel, a hydraulic cylinder for 35 yieldably resisting movement of the core towards the discharge end of the vessel, provided with a piston member adapted at the end portion of the concentrating period to hydraulically effect functioning of said 40 means for stopping feed of material and starting feed of water to the vessel, substantially as described.

3. In a centrifugal concentrator, the combination of a rotatable concentrating vessel, a differentially rotatable longitudinally movable core, within the vessel, adapted in operation to be pressed towards the discharge end of the vessel, hydraulically actuated means for feeding material and feeding water to 50 the vessel, a hydraulic cylinder for yieldably resisting movement of the core towards the discharge end of the vessel, provided with a piston member, adapted, on reaching the discharge end of the vessel, to 55 hydraulically effect functioning of means embodying the hydraulically actuated feed valve mechanism for closing the feed of material and opening the feed of water to the vessel, substantially as described.

60 4. In a centrifugal concentrator, the combination of a rotatable concentrating vessel, differentially rotatable longitudinally movable core, within the vessel, adapted in operation to be pressed towards the discharge 65 end of the vessel, hydraulically actuated

means for feeding material and feeding water to the vessel, a hydraulic cylinder for yieldably resisting movement of the core towards the discharge end of the vessel, provided with a piston member adapted, on 70 reaching the discharge end of the vessel to hydraulically effect functioning of means embodying the hydraulically actuated feed valve mechanism for closing the feed of material and opening the feed of 75 water to the vessel, and means for effecting hydraulic functioning of said mechanism at the beginning of the concentrating period to close the water and open the feed of material to the vessel, substantially as de- 80 scribed.

5. In a centrifugal concentrator, the combination of a rotatable concentrating vessel, a differentially rotatable longitudinally movable core, within the vessel, adapted in 85 operation to be pressed towards the discharge end of the vessel, hydraulically actuated means for feeding material and feed water to the vessel, a hydraulic cylinder for yieldably resisting movement of the core 90 towards the discharge end of the vessel, provided with a piston member adapted, on reaching the discharge end of the vessel to hydraulically effect functioning of means embodying the hydraulically actuated feed 95 valve mechanism for closing the feed of material and opening the feed of water to the vessel, and means for effecting hydraulic functioning of said mechanism at the beginning of the concentrating period to close the 100 water and open the feed of material to the vessel, embodying a governor adapted to open a hydraulic flow pressure channel at concentrating speed of the vessel, substantially as described.

6. In a centrifugal concentrator the combination of a rotatable vessel, a differentially rotatable longitudinally movable core within the vessel, adapted in operation to be hydraulically pressed towards the discharge end of the vessel, yieldable hydraulic means for resisting such endways pressure, means for feeding material and feeding water to said vessel, at desired times, and means for hydraulically operating said feed 110 means in part governed by accretion of heavier constituents in the vessel, substantially as described.

7. In a centrifugal concentrator the combination of a rotatable vessel, a differentially rotatable longitudinally movable core within the vessel, adapted in operation to be pressed towards the discharge end of the vessel, in part by accretion of heavier constituents in the vessel, yieldable hydraulic means for resisting such endwise pressure, means for feeding material and feeding water to said vessel, means for hydraulically operating said feed means embodying a governor for effecting hydraulic functioning of 120 125 130

said feed means for starting feed of material at concentrating speed of the vessel, substantially as described.

8. In a centrifugal concentrator, the combination of a rotatable vessel, a differentially rotatable longitudinal movable core within the vessel, adapted in operation to be pressed towards the discharge end of the vessel, a shaft for supporting and rotating the core, a hydraulic cylinder adapted to contain liquid under pressure for yieldably resisting the endways pressure on the core, and adapted to receive the end portion of said shaft, a piston head within said cylinder, hydraulic valve mechanism connected to said cylinder, adapted to be operated by mechanism of the cylinder at the end of the concentrating period, means for feeding material to the vessel, a hydraulic cylinder adapted to operate said feed means, functioned by liquid from said core resisting

cylinder, and means for hydraulically connecting said latter cylinder and said valve operating cylinder, substantially as described.

9. In a centrifugal concentrator, a combination of a rotatable vessel, a differentially rotatable longitudinally movable core within the vessel, adapted in operation to be pressed towards the discharge end of the vessel in part by accretion of heavier constituents in the vessel, yieldable, hydraulic means for resisting such endways pressure, means for feeding material and feeding water to the vessel, at desired times, means for automatically hydraulically operating said feed means, at undetermined periods, and for automatically hydraulically opening feed of material to the vessel resultant to concentrating speed of the latter, substantially as described.

ORRIN B. PECK, JR.
